FLEXIBLE CORRUGATED HOSE OR THE LIKE

Peter H. Seckel, 13 Miller Place, Wayne, N.J. 07470

Filed Nov. 26, 1965, Ser. No. 88,218

Term of patent 14 years

(Cl. D43—1)

FIG. 1

FIG. 2

FIG. 3

FIG. 4

FIG. 5

FIG. 6

FIG. 7

FIGURE 1 is a side elevation view of the flexible corrugated hose embodying my new design with portions broken away to show indeterminate length;

FIGURE 2 is an end elevation view thereof;

FIGURE 3 is a cross-section taken on line 3—3 of FIGURE 1;

FIGURE 4 is a cross-section taken on line 4—4 of FIGURE 1;

FIGURE 5 is a view similar to FIGURE 1 and showing a modified form of the flexible corrugated hose embodying my new design;

FIGURE 6 is a cross-section taken on line 6—6 of FIGURE 5; and,

FIGURE 7 is a cross-section taken on line 7—7 of FIGURE 5.

I claim:

The ornamental design for a flexible corrugated hose or the like, substantially as shown and described.

UNITED STATES PATENT OFFICE

Certificate

Patent No. D. 206,387

Patented December 6, 1966

Peter H. Seckel

Application having been made by Peter H. Seckel, the inventor named in the patent above identified; Franklin Dick of New York City, New York; and Rexall Drug and Chemical Company, Los Angeles, California, a corporation of Delaware, the assignee, for the issuance of a certificate under the provisions of Title 35, Section 256, of the United States Code, adding the name of the said Franklin Dick as a joint inventor, and a showing and proof of facts satisfying the requirements of the said section having been submitted, it is this 3rd day of December 1968, certified that the name of the said Franklin Dick is hereby added to the said patent as a joint inventor with the said Peter H. Seckel.

EDWIN L. REYNOLDS,
First Assistant Commissioner of Patents.
